UNITED STATES PATENT OFFICE

126,441

DESIGN FOR AN IRONING BOARD BRACKET

Stephen F. Slawski, Culver City, Calif.

Application August 24, 1940, Serial No. 94,612

Term of patent 14 years

To all whom it may concern:

Be it known that I, Stephen F. Slawski, a citizen of the United States, residing at Culver City, county of Los Angeles, and State of California, have invented a new, original, and ornamental Design for an Ironing Board Bracket, of which the following is a specification, reference being had to the accompanying drawing, forming part thereof.

Fig. 1 is a plan view of an ironing board bracket showing my new design in full lines.

Fig. 2 is a sectional view on line 2—2 of Fig. 1.

The dominant features of my design reside in the portions shown in full lines.

I claim:

The ornamental design for an ironing board bracket, substantially as shown and described.

STEPHEN F. SLAWSKI.
